CEMENT MIXING APPARATUS

Joseph E. Pipes, Olney, Tex.

Application July 11, 1935, Serial No. 30,785

1 Claim. (Cl. 83—73)

This invention relates to cement mixing apparatus and it has particular reference to an apparatus designed especially for mixing cement preparatory to use in cementing wells.

5 The principal object of the invention is to provide an apparatus of the character specified embodying a structure which can be readily and thoroughly cleaned after having been used, thereby to prevent accumulations of cement therein, 10 which, having become set, renders the machine difficult to operate.

Another object of the invention is to provide a compact machine which is an attachment in the cementing of wells and particularly oil wells since 15 it is necessary that the apparatus be transported from place to place on a truck or the like and it is sometimes required that the apparatus be moved great distances in inclement weather. The compactness of the present invention, its ease of 20 operation and cleaning renders the same exceptionally advantageous for the purpose for which it has been designed.

Still another object of the invention resides in a novel form of mixing element, the construction 25 being designed for rapidly and thoroughly mixing the water and cement in a confined space preparatory to its introduction into the well. Moreover, the invention includes a novel form of water control which prevents clogging of the throat of the 30 mixer hopper and supplies the mixer continuously with a predetermined quantity of water at a uniform flow.

With the foregoing objects as paramount, the 35 invention has particular reference to its salient features of construction and arrangement of parts which will become manifest as the description proceeds, taken in connection with the accompanying drawing, wherein:—

Figure 1 is an elevational view of a mixing 40 apparatus constructed according to the present invention with portions broken away to show internal parts and which further shows fragmentarily the water supply.

Figure 2 is a detail view of the mixing element.

Figure 3 is a transverse section on lines 3—3 on Figure 2.

Figure 4 is a fragmentary view in vertical section showing the hopper and water control.

50 Figure 5 is a detail view in elevation showing the agitating element disposed in the throat of the hopper, and

Figure 6 is a perspective view showing the water control inlet.

55 Continuing with a more detailed description of

the drawing, 1 designates a hopper into which neat cement is initially deposited preparatory to mixing with water for introduction into a well.

Ordinarily, a mixing cylinder is employed, necessitating a shaft having mixing paddles thereon. 5 The present invention dispenses with both the cylinder and the shaft and provides in lieu thereof a depending chamber 2 having a rounded bottom 3, and is of a diameter not exceeding that of the throat 4 of the hopper 1. The fact that the hopper is bowl shaped or has a rounded bottom and does not extend beyond the limits of the hopper throat, enables the operator to see and thoroughly cleanse the mixing chamber of accumulations of 10 cement to prevent clogging after an operation of 15 cementing a well.

The mixing element confined for operation in the mixing bowl 2 is composed of a circular band 5 of semi-circular shape in cross-section, which is welded or otherwise suitably secured to the shaft 6. A smaller circular band 7 is also and similarly secured to the shaft 6 and is positioned in a plane passing through the axis of the shaft and at an angle to the plane in which the band 5 is positioned. A still smaller band 8 is also welded 20 to the shaft 6 and is likewise disposed at an angle to the planes in which bands 5 and 7 are positioned. This arrangement is such that a thorough mix of cement and water within the bowl 2 is obtained yet does not allow accumulations of 25 30 mixture in the bowl.

In order to insure uniform flow of the cement as it is fed into the mixing bowl, an agitating element in the form of a shaft 9 is provided which has a series of radially extending pins or fingers 35 10 which are effective in continually feeding the cement into the mixing bowl so as to break up any 40 clods or lumps of cement which might be formed by moisture.

During the feeding of cement into the bowl 3, 40 water is added through the medium of a pipe 11, shown in Figure 1, from the liquid reserve tank 12, shown fragmentarily in Figure 1. The water control is comprised of a chamber 12 into which water is initially introduced through pipe 11 from 45 the reservoir 13. This chamber communicates with the hopper 1 through an opening 14, partially covering which is a plate 15, shown in detail in Figure 6.

The plate 15 is so disposed over the water inlet 50 opening 14, that water is directed downward in a fan shaped spray, thereby continuously flushing the hopper and preventing accumulations of cement in the hopper throat.

After having been thoroughly mixed in the bowl 55

3, the mixture is deposited into the receptacle or sump 16 through the discharge pipe 17 from which it is removed and conveyed to the well by pump suction through pipe 18.

5 What is claimed is:

The combination in a cement mixing apparatus, a bowl, having a spherical bottom and a hopper whose throat conforms to the top of said bowl, a water inlet and control in the throat of

10 said hopper, a shaft rotatably disposed in the top of said bowl having radially disposed fingers

throughout its length, whereby to agitate and effect transfer of cement from said hopper into said bowl, a mixing element in said bowl comprising a plurality of circular bands of different diameters each being positioned on a shaft in a plane passing through the axis of said shaft and at angles relative to the planes in which the companion bands are positioned on said shaft and means for discharging the mixture from said bowl.

5

JOSEPH E. PIPES.
